UNITED STATES PATENT OFFICE.

JOHN WERNER, OF WHITE SULPHUR SPRINGS, MONTANA.

STOVE-COVER LIFTER.

No. 892,697.

Specification of Letters Patent.

Patented July 7, 1908.

Application filed October 29, 1907. Serial No. 399,785.

To all whom it may concern:

Be it known that I, JOHN WERNER, citizen of the United States, residing at White Sulphur Springs, in the county of Meagher and State of Montana, have invented certain new and useful Improvements in Stove-Cover Lifters, of which the following is a specification.

My invention relates to stove cover lifters and has for its object to provide a lifter that may be not only used conveniently in handling stove covers but readily adapted to fit the different size sockets in the stove covers and thus become a universal stove cover lifter.

The following specification will show the construction and mode of combining the parts and the means whereby the objects in view are accomplished when taken in connection with the drawings accompanying the same and forming a part hereof.

Figure 1 is a plan view of one form of my device. Fig. 2 is a longitudinal sectional view drawn through line $y-y$ of Fig. 1. Fig. 3 is a side view of one of the jaws. Fig. 4 is a side view of the spring between the two jaws. Fig. 5 is a cross section through line $x-x$ of Fig. 1. Fig. 6 is a top or plan view of a modified form. Fig. 7 is an inside view of one of the jaws with a longitudinal section of the binding or pivoting strap.

Referring to the drawings 2 designates one form of my device 4 the jaws and 5 the two parts composing the handle. Each part of the handle consists of a rectangular bar recessed or hollowed out at 6 and provided with a shoulder 8 one on each side. The jaw 4 is shaped as shown in Fig. 3 and recessed out at 10. Integral with the jaw 4 is an arm 12 also recessed out at 14, and said arm adapted to slide into the recess 6 of the handle or part 5. This arm is also cut away on one side at 15 so that when the arm is inserted in the handle 5 the outside of the part of jaw 4 will be flush with the shoulder 8 on the handle. In the outer side of the arm is a socket 16 (shown in dotted lines in Figs. 2 and 3) in which is set a coil spring 18 adapted to engage and press against the inner side of the handle 5 and hold the jaws 4 and the handle at an angle to each other. These springs may be done away with and a single spring 20 as shown in Fig. 4, inserted between the two arms of the jaws in their recesses 10 and throw outward the two parts of the

handle and the points of the jaws into contact with each other.

Longitudinally around the two parts of the handle 5 is a binding pivoting strap 22. Its forward ends 24 are provided with holes in which pins 25 are inserted and extend through the handle 5 and arms 12. These pins form pivots for each part of the handle and each of the jaws and since these pins are inserted through holes in opposite sides or edges of the ends 24 of the binding strap 22 they will hold both jaws in contact with each other and both parts of the handle away from each other with the spring 20 compressed between them or the springs 18 compressed behind each arm.

Figs. 6 and 7 show a modified form. In this form each of the jaws 4 and the handle 5 are made integral and hollowed or recessed out at 28 whereby the lifter is light in weight and always cool. In the rear end of the inner side of each handle is a socket or hole into which a coil spring 28 is inserted and keeps the outer ends of the two parts of the handle normally out of contact with each other and the outer ends of the jaws in contact with each other. These two jaws and handles combined are pivoted to the strap 22 through holes in the ends 24 by pins 25 in the same manner as the lifter shown in Fig. 1.

The manner of operating the device will be readily understood as when it is in normal condition and not in use the outer ends of the jaws are in contact with each other and the rear ends of the handle are separated. The operators simply insert the jaws in the socket within the cover and in the grasp to raise the cover it brings the outer ends of the handles toward each other and the points of the jaws outward against the sides of the socket in the cover.

It will be seen that by means of the strap 22 to which the two parts of the handle are pivoted, that there will be no danger of pinching the hand of the operator while the other ends of the two parts of the handle are forced into contact with each other and the handle will be kept cool by the air within the handle and it will readily adjust itself to sockets in covers of different widths and sizes.

Having now described my invention what I claim is:—

1. An adjustable stove cover lifter, consisting of two parts constituting the jaws and

handle, a spring between the two parts, and a strap extending longitudinally around the handle to which the two parts are pivoted.

2. An adjustable stove cover lifter consisting of the combination of a handle made in two parts with a jaw for each part; a spring between the parts of the handle; and a strap extending longitudinally around the handle to which the two parts of the lifter

are pivoted and said strap covering the space 10 between the two parts of the handle.

In testimony whereof I affix my signature, in presence of two witnesses:

JOHN WERNER.
